UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

OVERSEAMING-MACHINE.

1,161,294.

Specification of Letters Patent. Patented Nov. 23, 1915.

Application filed October 30, 1912. Serial No. 728,546.

To all whom it may concern:

Be it known that I, ALBERT H. DE Voe, a citizen of the United States, residing at Westfield, in the county of Union and State 5 of New Jersey, have invented certain new and useful Improvements in Overseaming-Machines, of which the following is a specification, reference being had therein to the accompanying drawings.

10 This invention relates to an improvement in overseaming machines, and especially to such machines used to apply an overseam binding to the edges of fabrics having curved outlines such, for instance, as the 15 soles of Japanese tabis.

The invention has for its object to maintain effective control of the work and insure uniformity of the overseam in stitching around curves, and more particularly to 20 insure the turning of the work upon the needle solely as a fulcrum.

In its preferred embodiment, the improvement is applied to that class of overseaming sewing machine employing a reciprocating and laterally jogging needle with suitable feeding mechanism, and it is secured by means of a presser-foot and automatically acting lifting means therefor periodically ineffective in performing its lifting 30 movements during the production of one or more stitches of a series or group.

In its broader aspect, the improvement is evidently applicable to machines of any kind wherein means are provided for producing relative lateral jogging movements 35 between the stitch-forming mechanism and the work.

In the accompanying drawings, Figure 1 is a side elevation, with the frame partly in 40 section, of a Singer overseaming sewing machine embodying the present improvement, and Fig. 2 a front end view of the same with the bed-plate in section. Fig. 3 is a 45 perspective view and Fig. 4 a sectional plan view of the upper feeding and presser-foot lifting mechanisms, the former being upon a larger scale than the preceding figures.

Fig. 5 is a perspective view of the presser-bar fulcrum-block detached. Fig. 6 is an 50 elevation of the actuating means for the upper feeding mechanism.

The frame is constructed with the usual bed-plate 1 to which is attached the bracket-arm comprising the hollow standard 2 and 55 laterally extending tubular member 3 ter-

minating in the hollow head 4 and having journaled therein the main-shaft 5 carrying the balance-wheel 6.

Journaled in the bracket-arm head 4 in a well known manner is the jogging needle-bar frame 7 in which is mounted the reciprocating needle-bar 8 carrying the needle 9. The needle-bar has fixed thereon the usual collar 10 carrying a lateral stud 11 slidingly connected with one end of the pitman 12 60 whose opposite end is connected with the usual crank-pin carried by the take-up cam-cylinder 13, the lower end of the link 12 being provided with a forwardly projecting lug 14 reciprocating within a slot 15 in the 65 guide-bar 16 secured to the bracket-arm head.

The needle-bar frame carries the forked lug 17 to which is pivotally connected by means of the screw 18 one end of the pitman 19 whose opposite end is adjustably secured by means of the screw 20 and nut 21 with the vibratory segment-arm 22, fulcrumed at 23 and formed in one face with the slot 24 to receive the screw 20. The 80 arm 22 carries the stud 25 entering the cam-slot 26 in the disk 27 provided with the bevel-wheel 28 meshing with the bevel wheel 29 fixed upon the main-shaft 5, as represented in dotted lines in Fig. 1. The lateral jogging movements are thus imparted to the needle through the cam-disk 27 and connected parts.

The bracket-arm is provided upon its rearward side with arms 30 and 31 each 90 carrying a center-screw 32 upon which is journaled the rock-shaft 33 parallel with the main-shaft and carrying at its rearward end the depending crank-arm 34 pivotally connected by means of the screw-bolt 35 95 with one end of a pitman 36 whose opposite end carries the stud-screw 37 whose head is fitted within the segmental-groove 38 of a depending arm 39 of the rock-shaft 40 journaled in bearing lugs 41 upon the standard 100 2. The stud-screw 37 is secured in position upon the arm 39 by means of the clamp-nut 42 in a manner well known.

The rock-shaft 40 has an upwardly extending arm 43 whose backwardly offset and forked extremity 43' carries a transverse pin 44 upon which is mounted the roller 45 maintained in contact relation with the actuating cam 46 upon the main-shaft 5 by means of the spring 47 having one end con- 110

nected with the arm 43 and the other end attached to the pitman 36. Through the means just described the upper feed rock-shaft 33 receives its operative movements.

5 Fixed upon the opposite end of the rock-shaft 33 from the arm 34 is a depending arm 48 having a forwardly offset portion 48' in which is swiveled the guide-block 49 having in its forward face the transverse guide-channel 50 and provided with the superposed cap 51.

Journalized to slide in said channel is the swinging feed-bar 52 pivotally mounted at its upper end by means of the stud-screw 53 entering a threaded transverse aperture 54 of the fulcrum-block 55 which is provided with a second aperture 56 entered by the presser-bar 57 to which it is secured by suitable means, such as a set-screw. To the reduced 20 and slotted lower end portion of the feed-bar 52 is adjustably secured by means of the screw 58 the shank 59 of the feeding foot 60 formed with serrated lower face and angular contour, as represented more particularly in Fig. 3. The bar 57 is forced downwardly by means of the usual spring 61 surrounding the same and interposed between the top of the fulcrum-block 55 and the top of the cavity in the bracket-arm head 4.

30 To the flattened upper end of the presser-bar is pivotally connected by means of the transverse pin 62 the forked head 63 of a slide-pin 64 journaled in the socketed and upwardly offset forward portion 65 of a lifting lever 66 whose rearward end is fulcrumed upon the pin 67 sustained by the bearing lug 68 upon the top of the bracket-arm. Intermediate its ends the lifting lever has pivotally attached thereto by means of 40 the pin 69 the forked upper end 70 of a plunger-rod 71 journaled in the bearing boss 72 upon the top of the bracket-arm and having mounted in its forked lower end by means of the pin 73 the roller 74 resting 45 upon the presser-lifting cam 75 fixed upon the main-shaft 5. The cam 75 is timed to lift the presser-bar, and hence the feeding foot 60, after each feeding movement.

Journalized in suitable bearing members 50 76 and 77 of the face-plate 78 secured to the head of the bracket-arm is the auxiliary presser-bar 79 having fixed thereto the collar 80 (Fig. 3) between which and the bearing member 77 (Fig. 1) is interposed the 55 spring 81 for forcing the presser-bar 79 normally downward. Secured upon the lower end of the presser-bar 79 by means of the set-screw 82 is a block 83 having an upwardly extending rigid arm 84 carrying the screw-stud 85 affording a fulcrum for the swinging lever 86 having secured to its transversely channelled lower end by means of the fastening screw 87 the shank 88 of the presser-foot 89.

60 65 The lever 86 has secured within a socket at

one edge by means of the screw 90 a straight wire spring 91 whose opposite end rests against the inturned end of a guide-plate 92 carried by the block 83 and having at the opposite edge of the lever 86 an inturned lip 93 provided with an adjustable stop-screw 94 whose point is adapted to engage the adjacent edge of the lever 86 and provided with a jam-nut 95. The auxiliary presser-lever 86 is thus adapted to yield laterally to enable the presser-foot 89 to follow the feeding movements of the feeding foot 60 and to spring back into normal position in contact with the stop-screw 94 when the auxiliary presser-bar is lifted.

70 The block 55 carries a forwardly projecting fulcrum-stud 96 entering an aperture in the outer extremity of the lateral arm 97 of an angle-lever having the depending arm 98 formed at its lower end with a transverse socket in which it is adjustably secured by means of set-screws 99 the pin 100 carrying the tappet piece 101 adapted to be engaged periodically by means of the stud 102 secured by means of the screw 103 upon an 75 arm 104 secured by means of fastening screws 105 upon the edge of the needle-bar frame 7 and partaking of the jogging movements of the latter. The angle-lever 97 80 98 carries at the junction of its arms a stud 106 85 upon which is fitted the slide-block 107 embraced by the forked outer end 108 of a rigid arm 109 projecting from a sleeve 110 secured by means of set-screws 111 upon the auxiliary presser-bar 79.

90 From the foregoing it will be understood that the formation of each stitch is succeeded by a feed movement which occurs when the needle is out of the fabric, and that when the needle is actuated to form the depth or left-hand stitch, the tappet 101 carried by the angle-lever 97, 98, is in contact with the stud 102 carried by the jogging needle-bar frame 7, and when the presser-bar 57 is moved vertically by the cam 75 carried by the main-shaft 5, the presser-foot 89 is given a like movement, but when the needle is actuated to form an edge or right-hand stitch the angle-lever 97, 98, is free to be rocked on its pivot stud 106, thus permitting the spring 110 115 81 to hold the presser-foot 89 in effective relationship with the fabric. The presser-foot 89 is thus held down upon the fabric except when the needle is forming a depth stitch, and the presser-foot actuating mechanism is 120 timed to give to said presser-foot vertical movements only when the needle is in the fabric in the formation of a depth stitch, making of the needle a fulcrum about which the fabric is turned when it is desired to effect a seam of curvilinear design.

125 As represented in the drawings, the face-plate 78 is formed with a slot to receive the angle-lever 97, 98, and with an outwardly extending guide flange 112, while the re- 130

duced opposite marginal portion of the face-plate has secured thereon, by means of screws as 113, a plate 114 formed with a guide-flange 115, and 116 represents the 5 throat or needle-plate. The fulcrum-block 55 is provided with a lug 117 which tracks a suitable groove (not shown) in the stationary part 118 of the hollow head 4, to hold the parts carried by the fulcrum-block 10 against axial movement, and the lug 119 forming a part of the fulcrum-block carries a bracket 120 to which is secured, by screws as 121, the tension-releasing finger 122 which acts to separate the thread-tension disks 123, 15 123, when moved upward by the action of the cam portion 124, of the presser-lifting lever 125, on the lug 119.

The under four-motion feeding mechanism herein employed is the same as is common to earlier sewing machine constructions, and as it has no particular bearing on the present invention reference will be made only to the most important elements.

126 represents the feed-dog mounted on 25 the feed-dog-carrying bar 127 pivotally connected at one end with the feed rock-shaft 128 which in turn is operatively connected by a rod 129 with the feed-cam 130 carried by the main-shaft 5, thus transmitting feed 30 movements from the latter to the feed-dog.

131 represents the feed-lift rock-shaft provided at its rear end with a crank-arm 132 carrying a roller 133 which coacts with a cam-disk 134 to give movements to the rock-shaft 131 and parts carried by it, the opposite end of the shaft 131 being provided with a crank-arm 135 carrying a roller 136 which acts on the under side of the free end 137 of the feed-dog-carrying bar to effect vertical 40 movements of the feed-dog.

138 represents an oscillating loop-taker provided with a thread-case 139 and driven by the loop-taker driver 140, the latter having formed integral with it a shaft 141 carrying a crank-arm 142 provided with a slide-block 143 which coacts with a forked arm 144 carried by a rock-shaft 145 mounted in a bearing formed in a bracket 146 depending from the under side of the bed-plate. The 50 rock-shaft 145 is provided with a crank-arm 147 suitably connected with one end of a connecting rod 148 whose opposite end is connected with a crank-disk 149 secured on the lower end of an upright shaft 150, the 55 upper end of which is connected by suitable gears as 151 with the main-shaft 5, thus transmitting oscillating movements from the latter to the loop-taker 138, as in earlier constructions.

60 Having thus set forth the nature of the invention, what I claim herein is:—

1. In a sewing machine, the combination with a reciprocating and laterally jogging needle, and a feeding mechanism engaging 65 the under surface of the fabric being acted

upon, of a presser-foot and feeding foot engaging the fabric at its upper side, means for effecting a feed movement of said feeding foot for each stitch-forming operation, and controlling means for raising said 70 presser-foot off the fabric only at each alternate stitch-forming operation, and while the needle is in the fabric.

2. In a sewing machine, the combination with a reciprocating and laterally jogging 75 needle for effecting edge and depth stitches, and a feeding mechanism engaging the under surface of the fabric being acted upon, of a presser-foot and feeding foot engaging the fabric at its upper side, means for 80 effecting a feed movement of said feeding foot for each stitch-forming operation, and controlling means for raising said presser-foot off the fabric only when forming a depth stitch, and while the needle is in the 85 fabric.

3. In a sewing machine, the combination with a jogging needle-bar frame provided 90 with a reciprocating needle-carrying bar, and a feeding mechanism engaging the under surface of the fabric being acted upon, of a presser-foot and feeding foot engaging the fabric at its upper side, means for effecting a feed movement of said feeding foot for each stitch-forming operation, and 95 controlling means including the jogging needle-bar frame for raising said presser-foot off the fabric only at each alternate stitch-forming operation, and while the needle is in the fabric. 100

4. In a sewing machine, the combination with a main shaft, a jogging needle-bar frame provided with a reciprocating needle-carrying bar, and a feeding mechanism engaging the under surface of the fabric being acted upon, of a presser-foot and feeding 105 foot engaging the fabric at its upper side, means including a cam carried by said main shaft for effecting a feed movement of said feeding foot for each stitch-forming operation, and controlling means including the jogging needle-bar frame for raising said presser-foot off the fabric only at each alternate stitch-forming operation, and while the needle is in the fabric. 110

5. In a sewing machine, the combination with a needle, a presser-foot having lifting and lateral movements, a feeding foot, means for actuating said feeding foot, and means for giving to the needle reciprocating and laterally jogging movements, of automatically actuated means for simultaneously lifting said feeding foot and presser-foot, and periodically actuated means for interrupting the lifting and lateral movements of said presser-foot for each alternate stitch. 120

6. In a sewing machine, the combination with a reciprocating and laterally jogging 130 needle and feeding mechanism including a

presser-foot, of means for effecting a feed movement of said feeding mechanism for each stitch-forming operation, and controlling means for raising said presser-foot off the fabric only at each alternate stitch-forming operation, and while the needle is in the fabric.

In testimony whereof, I have signed my name to this specification, in the presence of two subscribing witnesses.

ALBERT H. DE VOE.
